PROCESS FOR THE SYNTHESIS OF 1-ALKYL-8-METHYL HEXAHYDROINDANONE-4

Nicholas A. Milas, Belmont, Mass., assignor to Research Corporation, New York, N. Y., a corporation of New York

No Drawing. Application June 20, 1941,
Serial No. 399,040

10 Claims. (Cl. 260—468)

1

In the synthesis of the antirachitic vitamins, the ketone Compound I constitutes an important intermediate product. The present invention deals with a new process for the synthesis of this ketone.

Compound I

Although R preferably is the hydrocarbon side-chain found in the natural antirachitic vitamins, it is not restricted thereto but may be hydrogen or any other monovalent aliphatic hydrocarbon radical.

The present process makes use of the well known diethyl adipate, Compound II, or any other suitable ester of adipic acid. Through the well known process of cyclization with metallic sodium or sodium ethylate in a suitable solvent, Compound II is converted to 2-carboethoxy cyclopentanone-1, Compound III.

NaOOC₂H₅

or Na

Compound III

Compound III is then alkylated to give Compound IV by heating it for several hours with 6-methyl-2-bromo or iodo heptane in the presence of sodium potassium alloy or potassium metal using a solvent such as toluene or xylene.

2

Compound III is then alkylated to give Compound IV by heating it for several hours with 6-methyl-2-bromo or iodo heptane in the presence of sodium potassium alloy or potassium metal using a solvent such as toluene or xylene.

Compound IV

When Compound IV is refluxed with sodium ethylate, the cyclopentanone ring opens and subsequently closes again but in a different fashion to produce Compound V.

Compound V

That Compound V is actually produced may be shown by the positive ferric chloride reaction which is not given by Compound IV because the latter contains no active enolizable hydrogen atom.

Compound V can also be prepared by hydrolyzing Compound IV with hot dilute sodium ethylate or barium hydroxide to give the open chain dicarboxylic acid Compound VI which upon esterification and subsequent cyclization in the

presence of sodium or sodium ethylate is easily converted to Compound V.

The diethyl ester of Compound VI has also been prepared by an alternative route through the reaction of α -bromo adipic ester, Compound VII, and methyl isohexylketone, Compound VIII, in the presence of zinc dust or wool and subsequently reducing catalytically the Compound IX.

When Compound V is treated with magnesium in ethyl alcohol or with sodium ethylate, the magnesio or sodio salt, Compound X, is formed which reacts with ethyl chloroformate to give Compound XI.

Compound XI is then treated with α -bromo or chloro glutaric diethyl ester in the presence of amalgamated zinc to give Compound XII.

This product, Compound XII, is easily dehydrated by heating with small amounts of iodine or p-toluenesulfonic acid to give Compound XIII.

Compound XIII is then hydrolyzed with alcoholic potash, and the tetracarboxylic acid, Compound XIV, formed is decarboxylated by heating with copper powder under reduced pressure to form Compound XV, in which the double bond has rearranged to conjugate with one of the carboxyl groups.

Compound XV can easily be esterified with absolute alcohol in the presence of an acid catalyst and the resulting Compound XVI cyclized according to the method of Dieckmann using metallic sodium or sodium ethylate in an inert atmosphere whereby Compounds XVII and XVIII successively are formed. Compound XVIII upon treatment with methyl magnesium iodide gives Compound I, the desired product, by a 1,4-addition.

Compound XVI, one of the key intermediates, can also be synthesized by the following alternative route. This proceeds through the preparation of the halogeno Compound XIX from Compound IV. Compound XIX is then easily converted to the phenoxy Compound XX by treatment with sodium phenolate.

When Compound XX is hydrolyzed with alkali and the salt formed is acidified with dilute hydrochloric acid, the acid Compound XXI is

40

45

50

55

60

65

70

75

formed, which latter, upon heating with copper powder, goes over easily to Compound XXII.

When Compound XXII is treated with δ -methoxy n-butyl magnesium bromide in anhydrous ether and the product is hydrolyzed in the usual manner, Compound XXIII is formed, which latter can easily be converted to Compound XXIV by heating with small quantities of iodine or p-toluene sulfonic acid, or by treating with thionyl chloride in the presence of a tertiary base. Compound XXIV can be easily hydrogenated catalytically to Compound XXV.

When Compound XXV is hydrolyzed with either hydriodic or hydrobromic acid Compound XXVI is formed, which latter can be converted to Compound XXVII by oxidation with chromic acid. The sodium salt of Compound XXVII is then treated with sodium cyanide and the nitrile formed is hydrolyzed by boiling with hydrochloric acid yielding Compound XXVIII. This

is esterified and the resulting diester dehydrated to form Compound XVI.

ing α -halogeno glutaric diethyl ester, in the presence of amalgamated zinc, on Compound XXII, followed by dehydration to form Compound XXIX.

Compound XXIX is then hydrolyzed with alcoholic potash, and the hydrolyzed product is partly decarboxylated by heating with copper powder to form Compound XXX.

Compound XXX is catalytically hydrogenated and the product hydrolyzed with hydrobromic acid to form compound XXXI.

Compound XXXI is then oxidized with chromic acid to Compound XXVII, followed by reaction with NaCN to form the nitrile compound, and the latter is hydrolyzed to Compound XXVIII from which Compound XVI can be prepared as described above.

Compound XVI can also be prepared by react-

A more detailed account of the principal and

novel reactions of the present process is to be found in the following:

Synthesis of 2-[1',5'-dimethyl-hexyl carboethoxy cyclopentanone-1—Compound IV

2-carboethoxy cyclopentanone-1 (94 g.) was dropped slowly into 22.9 g. of potassium sand in 635 g. of anhydrous xylene heated in an oil bath to 125-130°. To this mixture was then added 150 g. of 6-methyl-2-iodo heptane and the mixture heated at 130-135° for 43 hours. After cooling to room temperature, water was added to the mixture and the xylene layer separated; the latter was washed three times with water, dried, and fractionated under reduced pressure, the product boiling at 165-170° (14 mm.) being collected; yield, 55 g.; B. P. at 3 mm. 142-146°; n_D^{18} , 1.4473. This ketone does not give a color with ferric chloride.

The ketone was also prepared in about 18% yields by using sodium-potassium alloy and the corresponding 6-methyl-2 bromo heptane and 2-carboethoxy cyclopentanone-1 and refluxing the mixture for 70 hours at 135-140°.

Synthesis of 5-[1',5'-dimethyl-hexyl-2-carboethoxy cyclopentanone-1—Compound V

Twenty-six g. of 2-[1',5'-dimethyl-hexyl carboethoxy cyclopentanone-1 was dissolved in the minimum quantity of absolute ethyl alcohol and to this was added 3 g. of metallic sodium. The mixture was then refluxed for eight hours, cooled, poured into water and neutralized with diluted hydrochloric acid. The aqueous mixture was extracted several times with ether, the ethereal extract was dried and thereafter was fractionated under reduced pressure, the product boiling between 190-205° (20 mm.) being collected and used for the next step. The fact of such a wide melting point range is probably due to the presence of cis and trans isomers in the mixture. This product gives the ferric chloride coloration while Compound IV does not, showing that it has undergone the rearrangement shown above.

Hydrolysis of Compound IV and preparation of Compound VI

Compound V may also be prepared from Compound IV via the Compound VI by hydrolyzing Compound IV in hot dilute alcoholic solution of sodium ethylate or by boiling for several hours with aqueous barium hydroxide. In both cases the salt of the acid Compound VI is formed. Compound VI can be obtained by acidifying with dilute hydrochloric acid and extracting with ether. By esterification and cyclization, Compound V may be formed. The diethyl ester of Compound IV can easily be prepared by heating Compound IV with absolute ethyl alcohol in the presence of small quantities of sulfuric acid.

The diethyl ester of Compound VI may also be prepared by reacting, in dry benzene, α -bromo-adipic ester VII with methyl isohexyl ketone VIII in the presence of amalgamated zinc dust or wool, using small amounts of iodine to catalyze the reaction. Product IX is isolated from the reaction and is easily converted to the diethyl ester product VI by catalytic hydrogenation in alcohol using platinum oxide or nickel catalyst.

Cyclization of the diethyl ester of Compound VI to form Compound V

The ketone Compound V is prepared by cyclization of the diethyl ester Compound VI using

the well known Dieckmann method by heating in toluene with metallic sodium. The principal product formed is ketone Compound V, which latter is separated by fractional distillation under reduced pressure.

Synthesis of 2,2 - dicarboethoxy - 5 - [1',5'-dimethyl]-hexyl cyclopentanone - 1—Compound XI

An equivalent quantity of Compound V is treated in anhydrous ether with one mole of ethyl-magnesium bromide, and to the product, Compound X, without separating it from the solvent, is added one mole of ethyl chloroformate; the mixture is well stirred for several hours. At the end of the reaction the product is treated with water, the ethereal solution is separated, and from the latter Compound XI is isolated and purified.

Synthesis of 1-carboethoxy-2-carboethoxybutyl-5-[1',5'-dimethyl]-hexyl - cyclopentene-Δ1,2—Compound XVI

Compound XVI is prepared by a series of simple reactions as follows:

Compound XI is heated in anhydrous toluene with an equivalent quantity of α -bromoglutaric diethyl ester in the presence of amalgamated zinc for several hours. The reaction is activated from time to time by the addition of small quantities of iodine. At the end of the reaction the product is poured in water and the toluene layer separated and dried. This gives Compound XII. When a few crystals of iodine or anhydrous p-toluene sulfonic acid is added and the mixture heated, water splits out and distils over yielding Compound XIII. Finally, the toluene is removed and the product saponified by heating on the water bath with 10% alcoholic potash. The mixture is then poured in water, acidified with hydrochloric acid and the organic acid extracted with ether. When the ether is removed and the tetracarboxylic acid, Compound XIV, heated with copper powder under greatly reduced pressure, the acid, Compound XV, distils over; this latter can easily be esterified with absolute alcohol in the presence of small amounts of sulfuric acid to form Compound XVI, which is purified by fractionation under reduced pressure.

Synthesis of ketone Compound I from Compound XVI

One mole of metallic sodium is treated in anhydrous toluene under reflux with vigorous stirring to produce finely divided sodium. To the mixture is then added slowly one mole of Compound XVI. After all of Compound XVI has been added, the mixture is heated for several hours, then cooled and poured in water and the toluene layer separated, dried and the toluene removed. The toluene-free residue is purified by fractionation under reduced pressure. The product, Compound XVII, is then saponified by heating on the water bath with alcoholic potash, poured into water, and the mixture is acidified with hydrochloric acid and extracted with ether. When the ether is removed from the extract the product, upon heating, loses carbon dioxide very easily to form Compound XVIII.

Compound XVIII is easily converted to Compound I by treating it in anhydrous ether with methyl magnesium iodide.

11

I claim:

1. As a new product, a compound of the formula

wherein Z is a substituent of the group consisting of hydrogen and a monovalent aliphatic hydrocarbon radical.

2. As a new product, a compound of the formula

3. Process which comprises cyclizing a compound of the formula

wherein Z is a substituent of the group consisting of hydrogen and a monovalent aliphatic hydrocarbon radical and treating the resulting product with methyl magnesium iodide to form a compound of the formula

wherein Z is a substituent of the group consisting of hydrogen and a monovalent aliphatic hydrocarbon radical.

4. Process which comprises cyclizing a compound of the formula

and treating the resulting product with methyl magnesium iodide to form a compound of the formula

12

5. In the process of producing a compound of the formula

wherein Z represents a substituent of the group consisting of hydrogen and a monovalent aliphatic hydrocarbon radical, the steps which comprise reacting a compound of the formula

wherein Z represents a substituent of the group consisting of hydrogen and a monovalent aliphatic hydrocarbon radical, with an alpha halogeno glutaric dialkyl ester in the presence of zinc, hydrolyzing the resulting product and dehydrating the hydrolyzed product to yield a compound of the formula

wherein Z represents a substituent of the group consisting of hydrogen and a monovalent aliphatic hydrocarbon radical, saponifying and decarboxylating the latter, and esterifying the decarboxylated product to yield a compound of the formula

wherein Z represents a substituent of the group consisting of hydrogen and a monovalent aliphatic hydrocarbon radical.

6. In the process of producing a compound of the formula

wherein Z represents a substituent of the group consisting of hydrogen and a monovalent aliphatic hydrocarbon radical, the steps which comprise substituting a metallo radical for the hydrogen in the 3-position of a compound of the formula

13

wherein Z represents a substituent of the group consisting of hydrogen and a monovalent aliphatic hydrocarbon radical, and thereafter replacing the metallo radical by a carboxyalkyl radical to produce a compound of the formula

wherein Z represents a substituent of the group consisting of hydrogen and a monovalent aliphatic hydrocarbon radical, reacting the latter product with an alpha halogeno glutaric dialkyl ester in the presence of zinc, hydrolyzing and dehydrating the resulting product to yield a compound of the formula

wherein Z represents a substituent of the group consisting of hydrogen and a monovalent aliphatic hydrocarbon radical, successively hydrolyzing and decarboxylating the latter, and esterifying the decarboxylated product to yield a compound of the formula

wherein Z represents a substituent of the group consisting of hydrogen and a monovalent aliphatic hydrocarbon radical.

7. In the process of producing a compound of the formula

wherein Z represents a substituent of the group consisting of hydrogen and a monovalent aliphatic hydrocarbon radical, the steps which comprise halogenating a compound of the formula

wherein Z represents a substituent of the group consisting of hydrogen and a monovalent aliphatic hydrocarbon radical, to introduce a halogen substituent in the 3-position, reacting the halogenated compound with sodium phenolate whereby to substitute a phenoxy radical for the halogen substituent in the 3-position, hydrolyzing with alkali and then acidifying with dilute mineral acid whereby to convert the —COO.alkyl group in the 1-position to —COOH, and heating the resulting carboxylic acid compound with cop-

14

per powder to produce a compound of the formula

wherein Z represents a substituent of the group consisting of hydrogen and a monovalent aliphatic hydrocarbon radical, treating the latter with δ -methoxy-n-butyl magnesium bromide in anhydrous medium and then hydrolyzing, whereby to form a compound of the formula

wherein Z represents a substituent of the group consisting of hydrogen and a monovalent aliphatic hydrocarbon radical, successively dehydrating, hydrogenating and hydrolyzing the latter, oxidizing the resulting 3-hydroxy compound with chromic acid to form a 3-keto compound, converting the 3-keto compound to the corresponding nitrile, and hydrolyzing with mineral acid to yield a compound of the formula

40 wherein Z represents a substituent of the group consisting of hydrogen and a monovalent aliphatic hydrocarbon radical, and successively esterifying and dehydrating the resulting product whereby to produce a compound of the formula

wherein Z represents a substituent of the group consisting of hydrogen and a monovalent aliphatic hydrocarbon radical.

55 8. Process of producing a compound of the formula

65 wherein Z represents a substituent of the group consisting of hydrogen and a monovalent aliphatic hydrocarbon radical, which comprises hydrolyzing a compound of the formula

75 wherein Z represents a substituent of the group

15

consisting of hydrogen and a monovalent aliphatic hydrocarbon radical, partially decarboxylating the hydrolyzed product to produce a compound of the formula

wherein Z represents a substituent of the group consisting of hydrogen and a monovalent aliphatic hydrocarbon radical, hydrogenating the latter and thereafter hydrolyzing the hydrogenated product, oxidizing the hydrolyzed compound to the corresponding 3-keto compound, converting the 3-keto compound to the corresponding nitrile, and hydrolyzing the latter to the corresponding dicarboxylic acid, esterifying the acid and dehydrating the resulting diester.

9. Process of producing a compound of the formula

wherein Z represents a substituent of the group consisting of hydrogen and a monovalent aliphatic hydrocarbon radical, which comprises hydrolyzing a compound of the formula

5

16

wherein Z represents a substituent of the group consisting of hydrogen and a monovalent aliphatic hydrocarbon radical, to yield a compound of the formula

10

wherein Z represents a substituent of the group consisting of hydrogen and a monovalent aliphatic hydrocarbon radical, esterifying the latter open chain dicarboxylic acid compound, and cyclizing the esterified compound.

10. Process of producing a compound of the formula

20

wherein Z represents a substituent of the group consisting of hydrogen and a monovalent aliphatic hydrocarbon radical, which comprises reacting an alpha-bromo adipic acid alkyl ester with methyl isoheylketone under conditions to yield a compound of the formula

25

30

40 catalytically hydrogenating the latter compound, and cyclizing the hydrogenated product.

NICHOLAS A. MILAS.
